UNITED STATES PATENT OFFICE.

SAMUEL J. ADAMS, OF DETROIT, MICHIGAN.

DEVICE FOR CLEANING FURNACE-FLUES.

1,202,012.

Specification of Letters Patent.

Patented Oct. 24, 1916.

Application filed December 10, 1912. Serial No. 735,887.

To all whom it may concern:

Be it known that I, SAMUEL J. ADAMS, a citizen of the United States of America, residing at Detroit, in the county of Wayne and State of Michigan, have invented certain new and useful Improvements in Devices for Cleaning Furnace-Flues, of which the following is a specification, reference being had therein to the accompanying drawings.

10 My invention relates to a device for cleaning furnace flues and has among the objects thereof to provide a simple and efficient means for thoroughly cleaning the flue; to provide a structure that may be readily applied to the furnace and if desired, may remain permanently in the flue without interfering with the operation of the latter.

15 Other objects of the invention will hereinafter appear.

20 The invention consists of the peculiar construction, arrangement and combination of parts as more fully hereinafter described and particularly pointed out in the claims.

25 While my invention may be readily adapted for various types of furnaces, it is especially designed for hot-air furnaces, and I will illustrate and describe the improvement applied to a furnace of the latter type.

30 In the drawings, Figure 1 is a horizontal sectional view taken through the flue of a hot air furnace, looking down on the cleaning device disposed within the flue. Fig. 2 is a sectional view taken on line X X of Fig.

35 1 and showing the cleaning device on a larger scale than the disclosure of Fig. 1. Fig. 3 is a sectional view taken at right angles of Fig. 2 showing the various parts of the cleaning device; Fig. 4 is a vertical sectional

40 view taken through a furnace construction showing the position of the device in the furnace.

45 In the usual construction of hot-air furnaces a flue such as A surrounds the firepot B and communicates with the pipe leading to the chimney, the flue being open as at C adjacent the fuel door D so that the interior of the flue at the front is accessible through the fuel door. As this flue is circular it is not readily cleaned, particularly the portion thereof at the back of the furnace.

50 With my improved device, however, the entire flue may be easily and quickly cleaned and the deposit in the flue drawn to the front of the furnace, from where it may be removed through the fuel door or dis-

charged through the dust passage E that leads to the ash-pit.

As shown, the device comprises an endless circular cleaner of a size to extend completely around the flue and formed of a plurality of spaced scrapers G secured together by connecting links H. Preferably the scrapers and the links are formed as an integral casting, while in order to allow the device to be applied to the furnace after the latter is assembled, the cleaner is formed of the links H of a size to be inserted through the fuel door into engagement with the flue. The meeting ends of adjacent sections have a 65 detachable engagement, as indicated at K.

The members G are each of a configuration to fit the cross-section of the bottom portion of the flue, but are of a height to project only a slight distance above the flue bottom 70 so as not to restrict the size of the flue to any appreciable extent. Thus, by moving the cleaning device around the flue as by engaging a hook L insertible through the fuel door with the scrapers, the deposit in the bottom 75 of the flue may be drawn to the front of the latter and removed.

In order to clean the side walls and the top portion of the flue I provide a brush M which is adapted to be secured to the circular cleaner F. This brush is of a width and height to engage the walls of the chamber A, and during the rotation of the endless member will efficiently clean the walls. The base N of the brush is longitudinally recessed at 80 O to receive a link H and carries a projection P at one end which is inserted through an opening Q in one of the scrapers.

R is an aperture extending transversely of the base adjacent the opposite end of the 95 latter, and S an opening in the link H adapted to align with the aperture R when the projections P are in engagement with the openings Q, and T is a bolt passing through the alining aperture and openings and serving to secure the base of the brush to the link H. At the front and rear the brush is protected by guards U. A central supporting web or arm L' formed integral with the base N is disclosed in Figs. 2 and 3 and provides 100 an additional supporting means for the brush.

In use, after the flue is cleaned the brush may be readily detached by removing the bolt T and disengaging the projections P 110 from the openings Q.

From the foregoing description it is ap-

parent that the cleaning member does not in any way interfere with the operation of the flue and therefore, can be made a permanent part of the furnace. Also the flue can be 5 cleaned while the furnace is in operation.

While I have shown and described the preferred form of my invention, I do not desire to limit my protection to the exact structure shown, but consider the invention sufficiently broad to cover various modifications and changes that may be readily made.

What I claim as my invention is:—

1. A flue cleaner including a sectional continuous flexible member, a series of scrapers 15 carried by said member and traversing the base of the flue and a vertically extending brush supported by said member, said brush contacting with the side walls of the flue and distributing the soot and foreign matter in 20 the path of the scrapers, the sections being of a size whereby the same may be separately inserted through an opening formed in the stove in which the cleaner is positioned.

25 2. The combination with a furnace having an annular flue, of an endless cleaning device located therein for movement thereabout and including a plurality of links connected together, scrapers carried by the 30 links of a contour to fit the bottom of the flue and resting thereupon, and operating means for the cleaning device, the flue having an opening whereby said operating means may be inserted within the same to 35 actuate the cleaning device.

3. A cleaner for the flues of furnaces in which the furnace is formed with an annular flue including a plurality of hingedly connected sections forming a continuous member disposed to traverse the flue at its base, 40 a series of scrapers carried by said members, and a brush supported by one of the members and extending vertically within the flue whereby the soot will be removed from the 45 sides of the flue and deposited within the path of the scrapers, the sections being of such configuration that the same may be inserted independently through an opening formed in the stove in which the device is 50 positioned.

4. The combination with a furnace flue of a cleaning device located for movement within the flue and including a scraper of a contour to fit the bottom portion of the flue, a brush of a width to engage the side walls of the flue and operating above the 55 scraper, and connecting means between the cleaning disk and brush cleaning device.

5. The combination with a furnace flue, 60 of a cleaning device located for movement within the flue and including a brush of a width to engage the side walls of the flue and operating above the scraper, protecting members for the brush supported at the 65 front and rear thereof for movement there-

with, and operating means for the cleaning device.

6. The combination with a furnace having an annular flue, of an endless flue cleaning device located therein for movement thereabout and including a plurality of connected links, scrapers carried by the links of a contour to fit the bottom of the flue and resting thereupon, and a brush of a width to engage the side walls of the flue, said brush being 75 provided with guards in front and rear thereof.

7. The combination with a furnace having an annular flue provided with an opening, and a door therefor, of a cleaning device 80 located within the flue and capable of a rotary movement thereabout, said cleaning device being composed of a series of pivoted members adapted to remain in the flue at all times, a support carried by the cleaning device, and a brush mounted upon said support, the said support being detachably mounted upon the cleaning device, and the brush and support being of a size to permit the insertion thereof within the flue 90 through the flue opening without disturbing the cleaning device located in the flue.

8. The combination with a furnace having an annular flue provided with an opening, a door therefor, a cleaning device located 95 within the flue and capable of a rotary movement thereabout, said cleaning device being adapted to remain within the flue at all times, and a brush detachably mounted on said cleaning device, the said brush being 100 of a size to permit its insertion through the flue opening in the wall of the furnace without disturbing the cleaning device.

9. The combination with a furnace having an annular flue of an endless cleaning device 105 located within the flue for movement thereabout, said cleaning device being provided with a scraper at the lower portion of the flue and a brush engaging the upper portion of the flue.

10. The combination with a furnace flue having an opening and a door therefor, of an endless cleaning device located within the flue for movement thereabout, said device including a plurality of sections, each of 115 said sections comprising a link having a cleaning member formed integral therewith, adjacent links being provided with detachable connections, each of said sections being of a size to permit the same to be inserted in place within the flue through the flue opening, and operating means for the cleaning device.

11. The combination with a furnace flue, 125 of a cleaning device arranged for movement within the flue, said cleaning device including a link member provided with a cleaning disk formed integral therewith and arranged to rest upon the bottom of the flue, said disk being provided with apertures, a 130

- brush engaging the upper portion of the flue and detachably secured to the link, said brush having a base provided with a recess to receive a portion of the link lugs at one end of the base of the brush engaging the apertures of the disk, and a movable pin passing through openings in the brush base and link at the other end of the brush, and operating means for said cleaning device.
- 10 12. The combination with a furnace having an annular flue provided with an opening, and a door for said opening, of a cleaning device located within the flue and capable of a rotary movement thereabout, and
- 15 including a support, said annular cleaning device being composed of a series of pivotally connected links and adapted to remain in the flue at all times, a brush detachably engaging said support and contacting with
- 20 the walls of the flue, the brush being of a

size to be inserted in place within the flue through the flue opening.

13. The combination with a substantially annular furnace flue, of a cleaning device comprising a member having a contour to fit the bottom portion of the flue and being restricted in height so as not to obstruct the flue, a link extending around the flue and to which said member is attached, and a brush of a width to engage the opposed walls of the flue and of substantially the same height as the latter, said brush being removably secured to said cleaning device.

In testimony whereof I affix my signature in presence of two witnesses.
